UNITED STATES PATENT OFFICE.

THOMAS A. HUTSELL, OF SPOKANE, WASHINGTON, ASSIGNOR TO THE HUTSELL MOTOR COMPANY, OF SPOKANE, WASHINGTON.

INTERNAL-COMBUSTION ENGINE.

1,361,332.

Specification of Letters Patent. Patented Dec. 7, 1920.

Application filed May 1, 1919. Serial No. 293,942.

To all whom it may concern:

Be it known that I, THOMAS A. HUTSELL, a citizen of the United States, residing at Spokane, county of Spokane, State of Washington, have invented certain new and useful Improvements in Internal-Combustion Engines, of which the following is a specification.

The present invention relates to improvements in internal combustion engines, and 10 contemplates new combinations and arrangements of parts affecting particularly the reception, compression and expansion of the fuel charge and the actions resulting in connection with the piston as it reciprocates in the cylinder and the invention also involves the utilization of a novel oil or lubricant distributing system in connection with the pistons. In order that the invention may be 15 readily understood I have illustrated a four 20 cylinder motor of the two-cycle type as used on automobiles, but it will readily be understood that a greater or less number of cylinders may be utilized if desired, the 25 present showing being an exemplification of the invention at the present time.

The invention consists in certain novel 30 combinations and arrangements of parts as will be hereinafter more particularly pointed 35 out in the specification and claims, and in the accompanying drawings I have illustrated one complete example of the physical embodiment of the invention constructed and arranged according to the best mode so far devised for the practical application of the principles of the invention.

Figure 1 is a side elevation of a motor or 40 engine involving the novel features of the present invention, one of the cylinders and a portion of the closed crank case being broken away for convenience of illustration.

Fig. 2 is an enlarged view, in section, 45 transversely of the engine, showing the piston in position with the exhaust open from the cylinder and a new charge entering the cylinder through a port diametrically opposite the exhaust port.

Fig. 3 is a similar view of the upper end 50 of the parts in Fig. 2, but here the piston is in position ready for ignition of the charge.

Fig. 4 is a view in elevation of the piston, 55 showing a portion of its stem broken away and the connecting rod attachment thereto.

In the preferred form of the invention as

illustrated in the drawings the usual closed crank case is employed as designated by the numeral 1, the fly wheel 2 and crank shaft 3, also being of usual and suitable construction. In the four cylinder engine shown, 60 the cylinders 4, 5, 6, and 7 are closed at their upper ends and open at their lower ends to the crank case, and provided with the usual water jackets 8 having the connections 8^a and 8' and the piston 9 reciprocating in the 65 cylinder and performing the required functions of a working piston for the engine and a pump piston for supplying the fresh charge to the engine. Thus the cylinder 4 in which the piston 9 works, has an annular 70 receiving compartment 9' forming the cylinder for the pump that supplies the fresh charge to the working part of the cylinder above the piston 9.

The piston has the usual connecting rod 75 10 coupled with the crank 3 and also coupled to a specially formed piston stem 11 which has a reduced end threaded at 12 into the piston head 13 to form an integral and rigid part thereof. The piston is of course 80 cylindrical and fashioned hollow with its interior and exterior machined or machine-tooled, and upon its working end is provided a semi-circular or annular flange or projection 14 forming a baffle wall to separate the gas of the fresh charge from the exhaust of the ignited charge and to guide the incoming fresh supply of fuel gas. At 85 15, 15, are indicated the usual packing rings 90 for the piston as it reciprocates in its cylinder, and near the upper end of the piston a circumferential slot 16 is provided forming a port in the piston which co-acts with a by-pass 17 in the cylinder wall that is controlled by the piston as it reciprocates, the 95 by-pass connecting the cylinder proper with its lower end 9' forming the pump cylinder before mentioned.

Within the lower end of the cylinder 4, 100 and forming the annular space 9' therein, is rigidly fixed an open end sleeve or sub-cylinder 18 over which the hollow piston 9 is adapted to telescope when at the end of its working stroke, and this sub-cylinder is 105 fashioned with an annular flange or ring 18' through which the bolts pass to secure the cylinders of the engine to the crank case. By this construction a rigid and fixed support is provided for the stem 11 of the piston and the piston is guided in a pos- 110

tively straight and true course as it reciprocates in its cylinder, thus assuring a close fit of the piston in the cylinder and consequently a stable movement of the parts to enhance the life of the motor.

The exhaust port 19 is diametrically opposite the by-pass 17, and the exhaust pipe 20 is connected with the cylinders in usual manner, while the intake port 21 alined 10 with the exhaust port receives the fuel supply from the manifold 22 through the check valve 23 as shown, the exhaust and intake ports being controlled by the reciprocating piston as usual.

15 During the up stroke of the piston the supply of fuel or charge, passes through the check valve and intake port to the annular space 9', the by-pass 17 being closed; then upon the return stroke of the piston 20 the check valve is closed by pressure from the under side of the piston and the charge is compressed in the pump cylinder 9', the gases receiving their maximum of compression when the piston reaches position just 25 before port 16 registers with the by-pass. When the by-pass is in line with the port 16 the compressed fuel charge passes up into the cylinder above the piston, expanding into the cylinder and aiding in scavenging 30 the exhaust gas through the port 19 which is open as indicated in Fig. 2. During the upward or return stroke of the piston the charge is compressed above the cylinder until the point of firing and at the proper 35 time charge is ignited and the cycle of the piston repeated, the firing taking place at the end of each upward stroke of the piston, and the exhaust of spent gas and compression of the fresh supply of gas taking place 40 on the downward stroke of the piston. The incoming or fresh charge of gas is proportioned so that its expansion will be slightly less than the capacity of the working cylinder, and consequently there is no likelihood 45 of loss of fresh gas through the exhaust, while on the other hand there may still remain a slight quantity of the spent gas in the cylinder, but much less than the usual quantity in many engines of this type.

50 It will be noted that the stem 11 of the piston receives the strain or lateral thrust occasioned by the action of the connecting rod and prevents its transmission to the piston itself, thus allowing the piston to 55 travel in a true line without wobbling with relation to the bore of the cylinder.

In Fig. 1 the oil pump 24 is actuated from the cam 25 whose shaft 26 is revolved by suitable connections from the engine, and 60 the oil is forced through the pipe line 27 to the main feed pipe 28 extending longitudinally within the upper part of the crank case. Each cylinder is provided with a branch feed pipe 29 leading from the main 65 pipe 28, and preferably a meter valve 30

is located at the junction of the main and branch pipes to control and regulate the passage of oil from the main through the branch pipes. The inner end of the branch pipe terminates in a plug 31 passing from 70 the lower end of the sub-cylinder or sleeve 18 to its inner bore, and this plug, which is open throughout its length is in position to register with the lower open end of a stand pipe 32 located centrally in the interior of the valve stem and bent outward to pass through the wall of the stem and register with the screw plug forming the termination of the branch pipe. During 75 the major portion of the movement of the stem communication is closed between the branch pipe and the stand pipe, but it will be apparent that oil is fed intermittently from the plug to the stand pipe when these parts register. As the oil accumulates in 80 the stand pipe of the stem it is gradually forced out into a reservoir 33 at the top of the piston stem, below the head, and through the radiating oil ducts 34 the lubricating oil passes from the reservoir to the 85 piston periphery to lubricate the piston. The piston may be of slightly less diameter where the ducts open out, than at other points to permit exit of the oil and then the oil passes around the piston and is distributed in the usual manner.

A predetermined quantity may be supplied from the pump, and so proportioned that after the required supply is furnished to the several cylinders, the excess oil passes 100 out of the end 35 of the main feed pipe and is used on the gears 36, 36, for the water circulation pump, the magneto, and other accessories.

The stem of the piston is lubricated by 105 the splash from the crank case in well known manner, and need not be described here.

From the above description taken in connection with my drawings it is evident that I have provided an engine that is well adapted for smooth running which reduces its vibration and enhances its durability, and which is highly efficient in performing its functions in connection with the reception, 110 compression and release of the charge into the working cylinder for ignition at the proper instant, and by the utilization of the construction for accomplishing the ends, the usual accessories including valves, shafts, 115 springs, tappets, etc. are eliminated to reduce the cost and operation of the engine, and to render it more simple in its operation. Advantage may be taken of the location of the exhaust and intake ports, which are alined, to heat the charge from the 120 exhaust if desired.

Because of the utilization of the telescoping piston and sub-cylinder and the arrangement of the by-pass and ports, I am enabled at all times to obtain a full charge at each 130

stroke of the piston regardless of the speed of reciprocation of the piston, and even on the slowest movement of the piston a full charge is obtained, so that efficient work can 5 be obtained and the engine made to quickly speed up when desired.

The water jacket is depended upon to cool the engine, but the piston, in addition is cooled, automatically, by the intake of 10 fresh charges, thus reducing the expansion of the piston and permitting a closer initial fit of the parts.

What I claim is—

1. The combination with the crank case 15 and cylinder communicating therewith, of a sleeve fixed in the lower end of the cylinder and forming an exterior fuel receiving and compression space, intake and exhaust ports to the cylinder and a by-pass in the wall of 20 the cylinder, a ported hollow piston in the cylinder co-acting with the intake and exhaust ports and said by-pass as described, and a concentric stem depending from the piston head and reciprocable in the sleeve.
2. The combination in an internal combustion engine, of a crank case and cylinder 25 opening thereto, a flanged sleeve bolted between the crank case and cylinder and occupying the lower end of the cylinder, said 30 sleeve forming an annular space between it and the cylinder and closed to the crank case, a hollow piston adapted to telescope into the annular space and provided with a hollow stem depending from its head, and

lubricating means within said stem for supplying lubricant to the piston and cylinder. 35

3. The combination with the cylinder having intake, exhaust and by-pass ports as described, of a sleeve in the lower end thereof forming an annular chamber, a hollow piston 40 adapted to telescope over said sleeve and provided with a port to co-act with said by-pass, and a stem on the piston guided in the sleeve as described.

4. The combination with the cylinder having an intake port, manifold, and a check valve in the manifold, a by-pass in the wall of the cylinder, and an exhaust port above the intake, of a sleeve in the lower end of the cylinder forming an annular receiving 45 and compression chamber to receive fuel from the intake, a hollow piston adapted to telescope into the receiving chamber and provided with a port to co-act with said by-pass and a stem on the piston guided in said 50 sleeve.

5. The combination with the cylinder having intake, exhaust and by-pass ports, of a sleeve in the lower end of the cylinder and a hollow piston adapted to telescope over the 55 sleeve and formed with a port to co-act with the by-pass, a hollow stem to the piston guided in said sleeve, and means for intermittently supplying oil to the piston through said stem. 65

In testimony whereof I affix my signature.

THOMAS A. HUTSELL.
